UNITED STATES PATENT OFFICE.

SHERMAN JACKSON, OF AKRON, OHIO, ASSIGNOR OF ONE-HALF TO LAWRENCE B. TROWBRIDGE, OF AKRON, OHIO.

POURING DEVICE FOR CONTAINERS.

Application filed October 16, 1924. Serial No. 743,964.

To all whom it may concern:

Be it known that I, SHERMAN JACKSON, a citizen of the United States, and a resident of Akron, county of Summit, State of Ohio, 5 have invented certain new and useful Improvements in Pouring Devices for Containers, of which the following is a specification.

This invention relates to pouring devices 10 for containers, particularly for granular or powdered substances and especially to a device designed for use on cans of explosive powder such as are used for blasting purposes in mines, quarries, or the like.

15 The purpose of the invention, in general, is to provide a device for the specific use above mentioned, which device will be simple and effective and will also comply with commerce laws in connection with the shipment of explosives. The several features of 20 the device, it is to be understood, however, are capable of general application to pouring devices for containers.

Heretofore in the shipment of powder in 25 cans or kegs, an opening has been provided in the top of the container which is usually circular in shape and is spaced inwardly considerable distance from the periphery of the top. This opening has generally been 30 closed by a cap, formed with a flange which is adapted to seat in a circumferential groove formed about the opening. The cap is retained in place over the opening during shipment by metallic clips secured onto the 35 top of the can and bent over the cap. It has been found that this structure will not permit of easy removal of the contents of the can, as for example, when pouring of the powder into cartridges. Moreover, two to 40 three pounds of powder in a twenty-five pound can will not pour from the can at all. Accordingly, miners frequently force an opening in the top of the can adjacent the periphery by the use of a pick. This 45 has resulted in numerous explosions with resulting loss of life and property.

The chief object, therefore, of the present invention is to provide a simple, effective pouring device, especially for use on powder cans, which can be securely held in place 50 during shipment in such a manner as to comply with the law and also a structure which is easy and inexpensive to manufacture.

The foregoing and other objects will be 55 come more apparent when the following de-

scription is read in connection with the accompanying drawings in which one form of the invention is illustrated, it being understood that the same is not limited to the specific form shown and described.

60 Of the accompanying drawings:

Figure 1 is a perspective view of a powder can provided with a pouring device embodying the invention;

Figure 2 is an enlarged detail plan showing the device closed for shipment;

Figure 3 is a section on line 3—3 of Figure 2;

Figure 4 is a section on line 4—4 of 70 Figure 3;

Figure 5 is a detail plan of the pouring trough;

Figure 6 is a side elevation thereof;

Figure 7 is an outer end elevation thereof;

Figure 8 is a detail plan of the slidable 75 closure plate;

Figure 9 is a side elevation thereof; and

Figure 10 is an outer end elevation thereof.

Referring to the drawings, 10 is a container, such as a powder can, provided with 80 the usual top 11 with the exception that the top 11 is formed with an opening 12 immediately adjacent its outer periphery. Part of the metal of the top 11, which is struck from opening 12, is bent over on opposite 85 sides of the opening to form flanges 13, 13 (Figure 4) and another portion thereof is employed to form a clip 14 for a purpose later to be described. At opposite ends of the opening, upstanding flanges 13^a, 13^a are 90 formed.

Adjacent the outer edge of the opening 11 the top is formed with a slot 15 (Figure 2), which is adapted to receive tongue 16, formed integrally on a pouring trough 17. 95 The trough 17 is formed of a single sheet of metal, so as to provide spaced outwardly bowed side walls 18, 18, having arcuate inner edges as shown at 19 (Figures 3 and 6) and formed with stops indicated at 20. 100 The top 21 of the trough 17, which when used for pouring acts as the bottom, but when the trough is not in use, provides a cover for the opening 11, is formed with flanges 22, 22 adapted to seat on flanges 13, 13 (Figure 4). The lower surface of the top 21 is adapted to seat on the flanges 13^a, 13^a (Figure 3). The arcuate edges 19 of walls 18 of the trough are adapted to pass through slots indicated at 23, extend- 110

ing inwardly of the top from the inner ends of the opening 12 on both sides of flange 13^a. Thus when the top 21 of the trough is seated on flanges 13, 13^a, the opening 12 will be entirely closed.

In order that the top 21 will be held tightly on the flanges 13 and 13^a, a retaining slide 24 is employed. The slide 24 is formed with bent under flanges 25, 25 on its opposite sides, which are so formed as to slidably embrace flanges 13 and 22 (Figure 4). The outer end 26 of the slide is curved substantially on a radius equal to the radius of the top 11, so that it will abut against a vertical flange 11^a extending about the periphery of the top 11. The inner end of the slide 24 is notched at 27 for the reception of the clip 14 which is adapted to be bent through notch 27 over the top of the slide 25 to retain it in place (Figures 2 and 3). On both sides of notch 27, the inner end of the slide is rolled into beads 28, 28, by which the slide 24 is adapted to be manually actuated.

In use, clip 14 is bent inwardly from the position shown in Figure 3, beads 28, are engaged by the finger nails and the slide 24 is drawn inwardly off of flanges 13 and 22, thus unclamping the trough 17. The inner edge of the trough is then engaged by the finger nails, and the trough is opened outwardly, against the resistance of the bowed walls 18 against the sides of opening 12 until the stops 20 engage the top 11. The can 10 may now be tilted, as will be understood, to pour the powder out of the can through the trough.

By clamping the flanges 13 and 22 together by the use of slide 24, which also urges the top of the trough against flanges 13^a, and then securing the slide 24 by the clip 14, the can is securely sealed for shipment in compliance with the law. The removal of the contents of the can may, however, be easily accomplished by the simple operations described above, the danger accompanying the improper use of the old

style of can, due to its inefficient operation, being entirely obviated.

Modifications of the invention may be resorted to without departing from the spirit thereof or the scope of the appended claims.

What is claimed is:

1. A pouring device for containers, comprising a container top having an opening therein adjacent its periphery, laterally extending flanges on opposite sides of the opening, a trough pivoted for movement in the opening, flanges on the trough adapted to seat on the first flanges, a slide formed with flanges on its under surface adapted to slidably embrace the first and second flanges to clamp them together and a metallic clip on the container adapted to be bent over said slide to hold it in place. 55

2. A pouring device for containers, comprising a container top having an opening therein adjacent its periphery, laterally extending flanges on opposite sides of the opening, a trough pivoted for movement in the opening, flanges on the trough adapted to seat on the first flanges, and a slide formed with flanges on its under surface adapted to slidably embrace the first and second flanges to clamp them together. 70

3. A pouring device for cans, comprising a container top having an opening therein, laterally extending flanges extending upwardly from the opening and formed from the metal of the opening, a trough movable in the opening adapted to seat on the flanges, and means for clamping the trough onto the flanges, said means including a metallic clip also formed from the metal of the opening. 75

4. A pouring device for containers, comprising a trough movable through an opening in the top of the container and a slide movable over the trough to retain the latter in closed position, said top and said slide having interengaging means thereon for locking said trough in its closed position and sealing said container. 90

SHERMAN JACKSON.
